G. E. PERRY.

TIME STAMP.

APPLICATION FILED MAY 12, 1913.

1,115,102.

Patented Oct. 27, 1914.

UNITED STATES PATENT OFFICE.

GEORGE ELLIOT PERRY, OF CHICAGO, ILLINOIS.

TIME-STAMP.

1,115,102.

Specification of Letters Patent.

Patented Oct. 27, 1914.

Application filed May 12, 1913. Serial No. 767,019.

To all whom it may concern:

Be it known that I, GEORGE ELLIOT PERRY, a citizen of the United States, residing at Chicago, in the county of Cook and State of Illinois, have invented certain new and useful Improvements in Time-
5 Stamps, of which the following is a specification.

My invention relates to improvements in
10 time stamps, and more particularly in some of its features to small, portable stamps adapted to be carried in the hand and in which the impression parts are inked from an ordinary inking pad.

15 Among the general objects of my invention is to provide a construction which is efficient, simple, cheap, and durable.

Among the objects specifically sought are relative smallness of size and convenience
20 of arrangement of parts of the stamp, so that it may be readily manipulated and held by three fingers with the stamp underlying the heel of the hand, so that the index finger and thumb may be used in assorting mail, or
25 the like.

Another object is to provide such construction that the horological motor is amply protected against undue shocks and jars, and is disposed for easy winding, setting,
30 and regulation.

A further object is to insure a clean, sharp impression from the time-impression means, however carelessly the stroke of the stamp may be made, and further to prevent
35 the horological motor from being subjected to any retardation or drag when the printing base of the device rests upon or is pressed down on a supporting surface, the arrangement provided by my invention being such that upon each stroke of the stamp
40 the time impression devices are momentarily brought into printing contact with the subjacent surface as a result of impact as distinguished from steady pressure.

45 Another object of my invention is to provide a construction in which the assembling in manufacture is particularly simple and inexpensive, and in which the interconnection between the various individual parts
50 is such that close interfitting is practically unnecessary.

In the drawings, wherein I have illustrated a practical embodiment of my invention; Figure 1 is a perspective view with
55 parts broken away showing the complete stamp; Fig. 2 is a central section there-

through with parts in elevation; Fig. 3 is an enlarged section on line 3—3 of Fig. 2; Fig. 4 is a perspective detail of a coupling connection and Fig. 5 indicates the character of the impression made by the stamp.

In the drawings, 10 indicates in general the stamp frame, of any suitable construction, preferably encased, and therefore, hereinafter referred to as a casing. Such casing comprises telescoping upper and lower casing sections 12 and 13 formed of thin sheet metal, connected with a stiff top plate 14 and base plate 15, for adequate strength. The casing may conveniently be
60 made substantially square in form, the true frame including posts 16 extending through the corners of the casing suitably fastened to the top plate 14, and having the base plate 15 secured to their lower extremities as by screws 17, so that no weight is carried by the thin casing walls. Upon the base plate is secured an impression member 18
65 preferably of rubber, or other resilient material, preferably bearing more or less printing surface including, in the structure shown, an annular clock dial 19. This impression member I will term the impression base, its lower surface being adapted to strike the surface to be printed and to define the printing plane. A handle 20 of convenient design to fit the heel portion of the hand is connected to the top of the frame or casing, preferably in such manner as will permit the universal angular displacement
70 75 80 of the handle relative to the top of the casing or to the printing plane. The specific construction shown provides, in attachment to the top plate 14, a cup 21 in which is seated a block of rubber 22, overlain by an inverted cup 23, secured to the handle 20 by a screw 24. Through an axial bore in the rubber and appropriate openings in the cups pass two hook members 25 interconnected to form a flexible joint at 26, substantially
85 90 95 100 centrally of the rubber body 22, one of said members preferably having a threaded stem receiving a nut 27 overlying cups 23, whereby the two cups 21 and 23 may be drawn more or less toward each other and the tension upon the rubber body correspondingly fixed as desired in the assembling of the parts.

30 indicates in general a horological motor preferably in the form of a watch provided with a winding and setting stem 31. The motor is supported in the casing in cushioned
110

arrangement with its stem 31 projecting through vertically elongated registering slots 32 in the casing members 12 and 13, and with its body guided and limited as to 5 horizontal movement by posts 16. Preferably a cushioning member is interposed between the motor and the top of the casing, the construction which I prefer providing a rounded boss or node 33 upon the upper side 10 of the motor frame or watch casing and a rubber sheet 34 interposed between the motor and the plate 14 of the casing. The motor is provided with an arbor 36 to be rotated at predetermined speed, (said arbor in 15 the present construction being the minute arbor,) arranged for connection to drive the time impression means of the stamp. The motor has also a suitable regulating lever 37, extending beyond the edge of the motor and 20 provided with an up-turned prong 37' confronting a suitable slot 38 made in the side wall of the casing to permit movement of the regulator by means of a pin or other thin instrument.

25 The movable impression means are carried by a floating carrier member, in the form of a plate 40, spring-positioned in relation to the bottom of the casing, or striking surface of the stamp, so as to move toward the bottom of the casing, under the influence of impact of the striking surface of the frame against the object to be printed. Under such impact the weight of the motor is also impressed upon the plate, and I provide between said plate and the motor, 30 springs to permit further movement of the motor relative to the plate after impact of the movable impression means upon the surface to be printed brings said impression 35 means to rest. In the specific construction shown, the floating plate 40 is of rectangular shape, provided with openings 41 for guidance upon the posts 16, said plate being positioned with reference to the bottom of the 40 casing by two light leaf springs 42 of arched shape having their ends notched as at 43 to engage appropriate ones of the posts 16 adjacent the areas of contact of said springs with the plate 40, and having their central 45 portions bowed downwardly for contact with the base plate 15 of the casing. Upon its upper side the plate 40 carries two spacing studs 45 which bear respectively against the arched central portions of a pair of relatively stiffer springs 46 (shown as each comprising two leaves) the slotted ends 47 whereof engage the stems of headed studs 48 carried by a motor-bearing-plate 49. This plate 49, directly underlying the motor, 50 has suitable apertures 50 for engagement with the four posts 16 and is suitably cut away centrally and along one side, as at 51, to provide a clearance opening for regulator lever 37 and for the central connections to be described. It will now be ap-

parent that if the stamp is struck downwardly upon a solid surface the momentum of the motor carries it downward after the impact stops the stamp frame, the relatively heavy springs 46 yielding but little while 55 the weight of the floating plate 40 and of the superposed motor forces said plate 40 downward against the resistance of the lighter springs 42, until the floating plate is positively stopped in its movement. Then 60 the springs 46 permit a further movement of the motor relative to the floating plate to prevent any uncushioned jar from affecting the motor, and upon the return of the motor to normal raised position, it is cushioned by the rubber pad 34.

The movable impression devices are carried by the floating plate, and consist in the present instance of a date slug and time impression means, the latter comprising concentric impression parts respectively adapted to register the minute and hour indications. In the construction shown the plate 40 bears on its under side a clip 55 holding a date indicating slug 56 (preferably of rubber) which works through a suitable slot 57 made therefor in the base plate 15 and the subjacent impression base 18. The hour impression part comprises a cup 60 fitting loosely in the central opening 51 in the printing base 18, and plate 15, said cup bearing an hour marker 62, in its rim, and having a tubular stem or sleeve 63 engaging the plate 40 for vertical movement therewith but for rotation relative thereto. A washer 64 is preferably arranged between the cup and plate to reinforce the bearing connection therebetween. The minute impression part comprises a rubber marker 67 carried by inner cup 68 fitting within the outer cup 60 and having its stem 68 extending through the central bore of sleeve 63 to project therebeyond. In the specific construction shown it is the shaft 69 of the minute indicator that has connection with the horological motor, the hour indicator being driven from the shaft 69 of the minute indicator by appropriate reduction gear mechanism carried by the floating plate 40. Specifically 70 indicates a small pinion upon the upper end of shaft 69, and 81 a gear immediately below it upon sleeve 63, a complementary gear 82 and pinion 83, connected together for rotation in unison, engaging respectively said pinion 80 and gear 81, and being mounted for rotation upon a stud 84 carried by plate 40. The shaft 69 of the time impression parts and the arbor 36 of the motor are articulated for rotative movement in unison but for relative vertical displacement, preferably by a universal joint which permits of some relative movement between the motor and the time impression devices vertically, horizontally, or tiltingly. In the specific construction shown the arbor 130

36 carries a U-shaped strap 90 through the legs of which slides horizontally a bar 91 having fixed to its center at right angles to its axis an arm 92, the downwardly extending fingers 93 at the extremity whereof engage elongated notches 95 in the upturned legs of a U-shaped yoke, 96 secured to the stem 69 of the minute time-impression part.

In the organization of the structure the 10 parts are so proportioned that the printing surfaces of the impression parts 62 and 66 stand normally in a plane considerably above the impression plane 19 of the impression base 18. Now it will be apparent that when 15 the stamp is struck, even lightly, upon an inking pad or surface to be printed, the impact throws downward the floating plate—which through yielding connections 42 carries the weight of the motor—against the 20 tension of the light spring 42, so bringing the time impression and date impression surfaces down to the level of the printing plane 19. As soon as the springs overcome the momentum of the motor, the parts are 25 instantly spring-returned to initial position. Thus the time impression surfaces make only a momentary contact with the inking pad or the surface to be printed, and produce a clear, sharp impression, regardless of 30 whether or not the printing base is struck against the surface to be printed squarely or in careless, slipping fashion. Also it is practically impossible to make an impression or to ink the stamp by imposing any amount 35 of pressure upon the casing or the handle, the time impression devices being carried too high above the surface 19 of the printing base 18 to be brought into contact with the surface to be printed by any mere compression 40 of the resilient pad 18. In point of fact, the pad 18 can be made rigid, as by the use of metal in lieu of rubber, if desired, for example, by reason of the use of the stamp in an atmosphere where the rubber 45 would not last. In any event the construction shown insures clearness of the time-impression without retardation of the motor.

I have herein described specifically a stamp which I have found in practice to be 50 efficient and satisfactory. It will be observed that the structure contains no parts difficult or expensive to manufacture; that it enables the use of an ordinary, inexpensive watch movement as the horological motor, that it facilitates assembling,—as substantially all of the detachable parts are simply strung upon the posts for guidance thereby—and that it makes substantially impossible 55 the injury of the mechanism or the disturbance of the connection between the motor and time impression devices by any amount of rough usage.

What I claim is:

1. In a time stamp, the combination of a 65 vertically unyielding frame providing on

one face a striking surface, time impression means located normally above the printing plane, guidedly and yieldingly supported in the frame for movement toward the printing plane under the influence of impact of 70 the frame against the surface to be printed, and a motor arranged to drive said time impression means.

2. In a time stamp, the combination of a vertically unyielding frame providing on 75 one face a striking surface, time impression means normally located above the printing plane and guidedly and yieldingly supported in the frame for movement toward the printing plane under the influence of impact of the frame against the surface to be printed, a motor positioned by 80 the frame, and driving connections between said motor and said impression means arranged to permit relative displacement of 85 said motor and said impression means.

3. In a time stamp, the combination of a vertically unyielding frame having a striking surface, a plate guided by the frame, springs between said plate and the striking 90 surface of the frame, time impression means carried by the plate normally located above the striking surface of the frame, and a motor arranged to drive said time impression means. 95

4. In a time stamp, the combination of a frame providing a striking surface, a motor guidedly and yieldingly supported in the frame for movement toward the printing plane under the influence of impact of the 100 frame against a resisting body, a time impression means normally located out of the printing plane and driven by the motor, and connections between said time impression means and the motor for movement of said 105 time impression means into the printing plane by movement of the motor in that direction.

5. In a time stamp, the combination of a frame providing a striking surface, a motor 110 guidedly and yieldingly supported in the frame for movement toward the printing plane under the influence of impact of the frame against a resisting body, a time impression means normally located out of the 115 printing plane, axially shiftable connections for rotation between the time impression means and a motor part, and resilient connections between the time impression means and the motor for movement of said time impression means into the printing plane by 120 movement of the motor in that direction.

6. In a time stamp, the combination of a frame having a striking surface, a floating plate guided in the frame, springs interposed 125 between said plate and the striking surface of the frame, a horological motor above the plate, stronger springs interposed between said horologic motor and the plate, and axially shiftable connections for rotation be- 130

tween a part of the motor and the time impression means.

7. In a time stamp, the combination of a frame, a horologic motor positioned by the frame, time impression means, and a universal joint connection between a part of the time impression means and a driving part of the horologic motor.

8. In a time stamp, the combination of a frame, a horologic motor guidedly and yieldingly supported relative to the frame, time impression means guidedly and yieldingly supported relative to the frame, and a universal joint connection between a time impression part and a driving part of the motor.

9. In a time stamp, the combination of a frame, a horologic motor guidedly and yieldingly supported relative to the frame, time impression means guidedly and yieldingly supported relative to the frame, and a universal joint connection between a time impression part and a driving part of the motor, said universal joint connection being arranged to permit relative vertical displacement between the motor and said time impression part.

10. In a time stamp, the combination of a vertically unyielding frame with a striking surface, a carrier member yieldingly supported in the frame for movement toward the striking surface under the influence of impact, time impression means carried by said carrier, and comprising impression parts movable at different speeds, gearing connecting said parts carried by said carrier, a horologic motor, and driving connection between said motor and one of said time impression parts.

40 11. In a time stamp, the combination of a frame, a motor supported in the frame, a floating carrier below said motor yieldingly positioned above the striking surface of the frame, hour and minute impression parts carried by the carrier and normally located above the printing plane, gearing connections between said hour and minute parts carried by the carrier, and a connection for rotation and for relative vertical displacement between a part of the motor and a time impression part.

12. In a time stamp, the combination of a frame providing guide posts and a striking surface, a motor guided in said guide posts, a floating plate guided in said guide posts, springs interposed between said motor and the floating plate, springs interposed between said floating plate and the striking surface of the frame, time impression device

60 carried by said floating plate normally positioned above the striking surface of the frame, and connections for rotation and for relative vertical displacement between the time impression part and a driving part of the motor.

65 13. In a time stamp, the combination of a frame comprising top and bottom plates and connecting posts, an impression surface carried by the bottom plate defining the printing plane and constituting the striking surface of the frame, a plate guided by the frame posts, springs below said plate, a horologic motor positioned laterally by the posts above the said plate, time impression means carried by said plate normally located above the printed plane, and vertically shiftable connections between a driving part of the motor and a time impression part.

70 14. In a time stamp, the combination of a frame comprising top and bottom plates, 80 posts connecting said plates, having one of said plates detachably secured thereto, a casing wall peripherally inclosing the space between said plates, a motor yieldingly supported within said casing, time impression means protruding from said casing, and vertically shiftable connections for rotation between a motor-part and a time impression part.

75 15. In a time stamp, the combination of a frame comprising top and bottom plates and connecting posts, a motor guided by said posts, a motor-carrying plate guided upon said posts, a floating plate below said motor plate guided upon said posts, springs interposed between the floating plate and the bottom of the casing, time impression parts carried by said floating plate, and connections for rotation and vertical displacement between the time impression parts and a rotatable motor-part.

80 16. In a time stamp, the combination of a frame, a horologic motor positioned with respect to the frame, time impression parts supported for movement in the frame, and 105 connections between a time impression element and a motor element, comprising a yoke having bifurcated ends on one of said elements, an arm engaged by said yoke, and a part in which said arm is laterally displaceably carried by the other element.

110 In testimony whereof I hereunto set my hand in the presence of two witnesses.

GEORGE ELLIOT PERRY.
